UNITED STATES PATENT OFFICE.

JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

SEWING-MACHINE GUIDE.

Application filed January 7, 1924. Serial No. 684,825.

This invention relates to sewing machine guides and more particularly to a form of guide adapted to facilitate the application of stitching of uniform depth upon an edge or superposed edges of material along which irregularities occur produced as by seams extending across the material transversely to the line of stitching to be applied thereto. Such irregularities, if they traverse a surface suitably disposed for guiding a regular margin or portions of material wherein no transverse seams occur, have a tendency during contact with said surface to deflect the material, especially where it is folded, and thus, for an interval, to produce an undesirable decrease in the depth of stitching applied. While imperfection of this sort is objectionable in edge finishing of various character, it is especially so in blind stitch hemming where a definite depth of stitch should be accurately maintained to insure proper inclusion of material within the edge enclosing stitches.

The provision of an edge guide mounted in a manner whereby it may be quickly shifted to compensate for the deflecting influence of marginal irregularities in the work is primarily the object of this invention. Further objects of the invention, as will hereinafter more fully appear, include the provision of an edge guide of the character mentioned in combination with trimming mechanism and a device to facilitate forming a blind stitch hem.

35 In the accompanying drawings,

Figure 1, is a view of a portion of an overseaming machine showing a preferred form of embodiment of my invention.

Figure 2, is a plan view showing a shiftable guide and its relation to certain other parts.

Figure 3, is a sectional view in a plane indicated by line 3—3 of Fig. 2, showing a guide and a gauge member in effective relation for blind stitch hemming.

Figure 4, is a detail view of transversely seamed material indicating the manner of folding the fabric to form a blind stitch hem.

50 Referring to the drawings, an overseaming machine of the Merrow type, (see United States Patents #733,760 and #1,094,858) is partially illustrated, wherein the stitch forming mechanism includes the needle 1,

and looper 2, which together with a lower looper (not shown) cooperate to form and apply overedge stitches to material comprising the work as it is advanced by feed mechanism across the work supporting plate 3, and needle plate 4, said feed mechanism including presserfoot 5, and feed dogs 6 and 7.

Mechanism operable in a well known manner for trimming the work simultaneously with the application of stitches thereon, is indicated in a general way by 8. It includes the normally stationary cutter 9, and a movable cutter 10, which are arranged for lateral adjustment by virtue of which to vary the distance between the line of trimming and the line of needle penetrations and thus to provide for obtaining any width of margin suitable to receive overedge stitching.

In the formation of a blind stitch hem, such as the machine illustrated is designed to produce, (see Fig. 4) an edge of material, as 12, prepared by the trimmers, is secured by overedge stitches to a folded edge 13, which is directed to receive the needle penetrations as indicated, by a guide 14, while the width of the fold may be determined by a gauge member 15. To permit of their lateral adjustment for normal cooperation in directing work to the stitching elements said edge guide and gauge member are mounted on a carrier or slide 16, the latter being in dovetail relation with a support 17, secured to the machine frame as by screw 18. Adjustment of the slide is effected by a knurled headed screw 19, threaded into support 17, and having a flange or collar in engagement with a groove 20, in said slide, the latter having associated therewith by screw 21, a clamping block 22, by means of which the slide, in any desired adjustment, 85 may be securely maintained against accidental displacement.

In Fig. 1, gauge member 15, is illustrated in a position in which it may readily be placed out of the way when not required for the work to be done, or temporarily out of the way to facilitate preliminary arrangement of material upon the work support preparatory to forming a blind stitch hem. After such preliminary arrangement of the work for hemming, the gauge member is swung to the position in which it is shown in Fig. 3, where it is effective both to hold

the stitch receiving folded edge of material in contact with guide 14, and to gauge the width of fold which determines the depth of hem to be produced. Any suitable arrangement 5 may be provided for moving the gauge to positions effective or non-effective as set forth, that shown comprises a pivotal joint including pin 24, a block 25, secured to slide 16, by screw 26, and a block 27, to 10 which the gauge member is secured by screw 28.

Referring now to guide 14, it will be obvious that its normal relation to the stitching elements, or that position in which it 15 is shown in Figs. 1 and 2, is suitable, when engaging an even uninterrupted edge of material, to direct said edge to receive needle penetrations along a line as indicated in Fig. 4. If this normal relation of the guide 20 were maintained during an interval when an irregularity of the fabric edge traversed the effective engaging surface of the guide, the material would be pushed beyond the alignment required to produce the desired result, 25 and frequently the amount of such displacement would result in failure of the needle to penetrate the material in the vicinity of the irregularity thereby causing "skipped stitches". Such objectionable displacement 30 of the fabric edge may be eliminated by slightly shifting the guide during contact therewith of an irregularity such as produced by a transverse seam as 23, see Fig. 4. To permit of thus shifting the guide it may, 35 about midway of its length, be pivotally secured to slide 16, by a screw as 29. Contact between one end of the guide and a shoulder 30, of slide 16, limits in one direction, such movement of the guide as that imparted by 40 a spring 31, which is held in a bore of the slide by screw 32. The position of the guide assumed under the influence of said spring is that which has been referred to as normal with respect to the stitching elements. To 45 compensate for such deflection of the work as would occur due to an irregularity in its edge, said guide, by suitable means, as by arm 33, may be moved by an operator against the pressure of spring 31, the amount 50 of such movement being limited in accordance with requirements by a stop, rendered adjustable by screw 32, and comprising a rod 34, surrounded by spring 31. While the edge guide may be conveniently controlled by 55 means of arm 33, it will be understood that additional means (not shown) operable as by foot or knee pressure, may be provided available for use in the event that both hands of an operator are required for manipulation of the work.

Having thus described my invention, what I claim is,—

1. In a sewing machine, in combination, a work support, a movable carrier, an edge guide secured to the carrier and movable thereon about an axis perpendicular to the work support, a spring for moving the edge guide to a normal position on the carrier, means for moving the edge guide from said normal position, and adjustable means for 65 limiting the amount of movement imparted to the edge guide.

2. In a sewing machine, in combination a work support, a movable carrier, an edge guide secured to the carrier and movable 75 thereon about an axis perpendicular to the work support, and a gauge member secured to the carrier and movable thereon about an axis parallel with the work support whereby it may be moved into position to cooperate 80 with the edge guide.

3. In a sewing machine, in combination, a work support, a movable carrier, an edge guide secured to the carrier and movable thereon about an axis perpendicular to the 85 work support, a spring for moving the edge guide to a normal position on the carrier, means for moving the edge guide from said normal position, and a gauge member movably secured to the carrier for cooperation 90 with the edge guide in different positions of the latter.

4. The combination in a sewing machine including a work support, stitching elements, and trimming devices, of a support, a carrier movable on the support, an edge guide, a gauge adapted to hold a fold of material against the edge guide and to cooperate with the edge guide and trimming devices to define an amount of material for a definite 100 depth of hem, means for associating the edge guide with the carrier whereby said edge guide may be moved to vary its relation to the stitching elements, means for associating the gauge with the carrier whereby said gauge may be moved out of proximity to the edge guide, and means for adjusting the carrier upon the support to thereby vary the relation of the guide and gauge to the stitching elements and trimming devices.

5. An attachment for facilitating blind stitch hemming on sewing machines, including in combination, a support, a carrier adjustably secured to the support, a shiftable edge guide secured to the carrier, means for automatically moving the edge guide to a normal position, and a gauge member secured to the carrier independently of the edge guide and movable on the carrier to different positions in one of which 115 it is effective to hold a fold of material against the edge guide in different positions of the latter.

JOSEPH M. MERROW.
